Patented Oct. 17, 1967

208,922

TEETER-TOTTER

Daniel P. Grudoski, Hartstown, Pa., assignor to Blazon,
Inc., Akron, Ohio, a corporation of Ohio

Filed Mar. 21, 1966, Ser. No. 1,569

Term of patent 14 years

(Cl. D34—5)

FIG.1

FIG.2

FIG.3

FIG.4

FIG. 1 is a perspective view, taken from one end of a rider and slightly above, and showing a teeter-totter incorporating my new design;

FIG. 2 is a plan view of a teeter-totter shown in FIG. 1;

FIG. 3 is an end elevation of a teeter-totter shown in FIGS. 1 and 2;

FIG. 4 is a side elevation of a teeter-totter shown in FIGS. 1, 2, and 3.

I claim:

The ornamental design for a teeter-totter, as shown.
